UNITED STATES PATENT OFFICE

2,576,669

ROTARY VALVE SPRAYER

George H. Bramhall, Cleveland, Ohio, assignor to
 General Electric Company, a corporation of
 New York

Application May 19, 1949, Serial No. 94,177

2 Claims. (Cl. 299—89)

1

This invention relates to a sprayer for atomizing liquids, and more particularly to a sprayer with a valve to control the quantity of material in the spray.

The utility of a sprayer is increased by providing a means for regulating the volume of material discharged in the spray. A suitable control for this purpose permits the sprayer to be used for many different applications and with various liquids. Several different arrangements for spray control can be devised. For example, the spray may be controlled by regulating the volume of air discharged at the spray nozzle. While such an arrangement may be satisfactory with hand sprayers, it is not particularly suitable for sprayers supplied from a motor driven source of compressed air designed to deliver a constant volume. Another construction for controlling the spray is in the form of a means for controlling the pressure within the receptacle or container for the material being sprayed. However, with such arrangements, it is difficult to provide a control system which is instantaneously responsive to the will of the operator. I find it preferable to provide a valve for regulating the flow of material to be sprayed to the spray nozzle.

It is, therefore, a primary object of my invention to provide a sprayer readily controllable by the operator to regulate the volume of material discharged in the spray.

It is also an object of my invention to provide a sprayer which, by the simplicity of its component parts, is economical to manufacture.

Another object is to design the parts so that they may be taken apart for easy cleaning.

A further object of my invention is to increase the ease with which the sprayer may be operated with a simplified adjustment to regulate the spray while the device is in use.

A still further object of my invention is to provide a sprayer particularly adapted for use as an attachment with vacuum cleaners.

For accomplishment of the foregoing objectives, a feature of my invention consists in employment of a rotary valve to control and regulate, at the will of the operator, the rate at which the material being sprayed may pass from a receptacle or container for such material to the spray nozzle.

The features of my invention which I believe to be novel are set forth with particularity in the appended claims. My invention itself, however,

both as to its organization and method of operation, together with further objects and advantages thereof, may best be understood by reference to the following description taken in connection with the accompanying drawing, in which Figure 1 is a side elevation, partially in section, of a sprayer constructed in accordance with my invention; Figure 2 is a plan view, partially in section, of the device shown by Figure 1; Figure 3 is a front elevation taken at right angles to the view shown by Figure 1; Figures 4 and 5 are partial cross-sectional views illustrating different positions of the valve employed with this sprayer.

Referring to Figure 1 of the drawing, I have shown a sprayer constructed in accordance with my invention adapted particularly for use with a vacuum cleaner. It is to be understood, of course, that my invention is not limited solely to use as an attachment for a vacuum cleaner, since this spraying device may be connected to any compressed air source of suitable pressure. A container or receptacle 1, for example, a glass jar, is adapted to receive a quantity of the material to be sprayed. The open mouth of container 1 is screw threaded to receive the spray cap or cover 2, formed as an integral unit of molded plastic or other suitable material. Cover 2 serves not only as a closure for container 1 but also as an air supply tube and a spray nozzle. The air supply tube 3 is adapted to be connected to an air supply conduit, such as a flexible hose. For the purpose of locking the air supply conduit (not shown) to the tubular portion 3, an annular groove 4 is provided for cooperation with a suitable latch on the air supply conduit. An air blast nozzle 5 is formed in the tubular portion 3 at its end opposite the point of connection to the air supply hose or conduit. This nozzle 5, in the form of an aperture of generally circular configuration, forms a port from which a blast of air issues during operation to atomize the material being sprayed. A discharge duct or passageway 6 terminates centrally of aperture 5. Thus, the material to be sprayed discharges into the core of the air blast and is immediately caught up by the rapidly moving air and broken into fine particles to form the spray. Discharge duct 6 is formed as a passageway through a block 7 which, in turn, may be molded integrally as a part of cover 2 along with the tubular portion 3.

To control the spray, a valve operating knob 8 is provided on top of cover member 2. Knob 8 is rotatable between fixed stops 9 and 10, as best shown by Figure 2. Extending downwardly from knob 8 is a cylindrical valve body 11. A supply tube 12 extends from near the bottom of container 1 upwardly and is inserted axially within valve body 11. Intersecting tube 12 within the valve body 11 is a short radial passage 13. Passage 13 opens into the tube 12 to form a passageway for the material being sprayed. Block member 7 on its end opposite the air blast nozzle has a semi-circular groove 14 to receive the valve body 11. The radial passage 13 in valve body 11 is coplanar with the passageway 6. To permit mounting of valve body 11 within the tubular portion 3 of the cover, a suitable aperture 15 is provided in the upper wall of air tube 3 and likewise an aperture 16 permits the valve body to extend into the container 1. Aperture 16 also serves to allow the air pressure within the air supply tube 3 to pressurize the content of container 1 in order to force the material to be sprayed up through tube 12.

Valve body 11 is held in firm contact with the semi-circular groove in block 7 by means of a spring 17. Spring 17 has a U-shaped clamping portion which engages the cover portion 18 of cover 2. The upper portion of spring 17, as shown by Figure 1, resiliently engages a notch or groove 19 on the valve body in a manner to prevent vertical displacement, and to force the valve body into firm contact with the semi-circular groove in block 7.

The operation of this device will be understood most clearly by a reference to Figures 4 and 5. Figure 4 illustrates the valve body 11 rotated to a position in which radial passage 13 is completely aligned with the discharge duct 6. In this position, it will be seen that the material to be sprayed may pass upwardly through the tube 12, outwardly through the radial duct 13, and into the discharge passage 6. Thus, with the valve adjustment shown by Figure 4, the maximum amount of material will be atomized in the spray. By rotating control knob 8 to its opposite limit, the valve is placed in the position shown by Figure 5. In this position, the liquid being sprayed is completely cut off from discharge duct 6. The operation of this device is also apparent from a reference to Figure 2. With the control knob 8 in the lower dotted line position and against stop 10, the valve is adjusted for full flow from receptacle 1. By a simple movement, the operator may then shift the operating knob 8 to the upper dotted line position against stop 9, in which case the flow of material to the spray nozzle will be completely shut off. If desirable, control knob 8 may be adjusted to any intermediate position between stops 9 and 10 to regulate the rate of spray of the liquid.

In accordance with this invention as described and illustrated above, a sprayer is provided which is instantly controllable to produce the desired spray. There is no need at any time to adjust or regulate the volume or pressure of air delivered to the air blast nozzle. Likewise, the contents of the container for the material to be sprayed are under the same air supply pressure at all times. The mechanism for controlling the spray is extremely simple to manufacture and readily assembled. The simplicity of the parts facilitates maintenance and cleaning and insures a long life for the sprayer.

While the present invention has been described

by reference to a particular embodiment thereof, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letter Patent of the United States is:

1. In a sprayer of the type having a container for a material to be sprayed and a cap engageable with said container, that improvement comprising an air supply tube as a part of said cap attachable to an air supply conduit at one end and defining an air blast nozzle at its other end, means within said tube and integral therewith defining a discharge passage for said material terminating adjacent said nozzle, and a valve member rotatably carried by said cap within said air supply tube, said valve member having a material supply tube extending to a point adjacent to bottom of said container and providing communication from said material supply tube to said means, an operating knob directly connected to said valve extending outside of said air supply tube, rotation of said valve member controlling the extent of communication to regulate the spray, and an air passageway around said material supply tube extending from said air supply tube through said cap to said container for supplying air to said container.

2. In a sprayer attachment of the type having a container for a liquid to be sprayed and a cap for said container, that improvement comprising an air supply tube on said cap for connection with an air source and defining an air blast nozzle, means within said tube and defining a passageway for liquid terminating at one end adjacent said nozzle, a valve member in said air supply tube, said valve member comprising a control handle therefor extending outside of said tube, a liquid supply tube extending into said container, and a conduit within said valve member providing communication from said liquid supply tube to said liquid passageway means, said valve member being rotatable with respect to said means, whereby rotation of said valve member by said handle controls the extent of communication between said conduit and said means, an air passageway adjacent said valve extending from said air supply tube through said cap to said container, and a spring clip engaged with said cap in said air passageway and resiliently urging said valve member against said liquid passageway means.

GEORGE H. BRAMHALL.
